UNITED STATES PATENT OFFICE.

LEO SHLICK, OF MONTREAL, QUEBEC, CANADA.

BEATING ENGINE.

Application filed February 17, 1921. Serial No. 445,737.

This invention relates to apparatus for the preparation of pulp in paper-making, and has for its object the effecting of certain improvements in the beater roll, the bed-plate, the tub itself, to means for removing strings and lumps of fiber from the stock, and for withdrawing entrained air and water from the stock before reaching the bed-plate, and for delivering this water to the stock after leaving the bed-plate.

Referring to the drawings forming part of this specification, Fig. 1 is a plan view of a beating engine embodying my improvements, certain parts being removed. Fig. 2 is a side view of the same, a part being sectional. Fig. 3 is a sectional view at right angles to Fig. 2. Fig. 4 is a longitudinal section of the beater roll. Fig. 5 is a cross section of the same. Fig. 6 is a section of the bed-plate. Fig. 7 is a sectional view of another form of the bed-plate.

The tub 1 is preferably made circular, with a hollow midfeather 2, and two diametrically opposed beater rolls 3, located in the annular channel 4, bed-plates 5 being disposed beneath each roll. The shaft 6 of each roll is supported in bearings 7 carried by lever arms 9 pivoted at 10 to the walls of the tub and midfeather, each arm having a rack 12 meshing with pinions 13 mounted upon a shaft 14. An arm 15 fixed to the shaft 14 and having a counterweight 16 serves to partially counterbalance the beater roll 3.

As shown in Figs. 1 and 3, the knives 17 on the beater roll are not parallel with the shaft, but are advanced at one end, so that the corresponding ends of the knives will reach the bed-plate 5 before their opposite ends, by preference the ends adjacent the wall 8 being the ones first to engage the bed-plate. These are not straight, but curved so that the convex edges move toward the bed-plate as the roll revolves; whereby the air entrained between the knives 17 is made to begin its lateral journey quite slowly, and then is made rapidly to increase it as the wall 11 is neared. Through the tub-wall 11 is a hole suitably screened and opening into a pipe 19 whose opposite end is connected with a suction pump of preferably the blower type, as 20, this hole 18 being beside the beater roll.

Hence, as the stock reaches the beater roll and bed-plate, and is acted upon thereby, the air entrained in the water and pulp

is forced along the blades 17 toward the hole 18, through which it is drawn by the suction pump, thereby materially reducing the volume of the stock being treated, and hastening the beater action.

Above the beater roll is located a hood 21 which passes over and beyond the same and then descends, as at 22, to compose one wall of a catch basin 23. At its opening 65 facing the roll 3 are suspended a series of rods 24 descending nearly into the mouth of a trough 25; and revolubly located above the catch basin 23 is a tubular shaft 26 provided with diametrically disposed arms 70 27 adapted to sweep along the rods 24 to the latter's extremities, for the purpose of clearing therefrom any strings or fibers clinging thereto. Further to aid this cleaning action, water is admitted into the tubular shaft 26, as at 29, which by its escape through perforations 28 in the shaft near the bases of the arms 27, flows down the latter to the ends of the rods 24 and thoroughly cleans therefrom all matter clinging 80 thereto.

As the stock surges toward the beater roll 3 and the bed-plate beneath it, a part thereof passes on about the midfeather and back to the beater mechanism again, but a 85 part is carried up over the beater roll, usually a part which has been reduced to a certain degree of fineness, and is thrown by centrifugal action into the catch basin 23. Any strings or lumps of pulp which may 90 be thrown with the fine pulp, are caught by the screen rods 24 and swept into the trough 25, as above described.

As a further improvement, the tub 1 is mounted on trunnions, as at 30 and 31, and 95 is provided with a screw rod 32 penetrating a lug 33 projecting from an end of the tub, as shown in Fig. 2, and anchored to the floor. By turning its hand wheel 34, the tub is brought to an even keel, or tilted to 100 a slight angle fore and aft, as may be desired for varying the circulation of the stock in the tub.

By having the arm 15 projecting in opposite directions from the shaft 14, the pressure of the beater roll 3 can be adjusted through a wide range, either to make it much less than normal, or much more, as may be desired for the work.

Although the pipe 19 may serve to withdraw the entrained air from the pulp being beaten, it also serves to remove a consider-

- able proportion of the water expressed from the pulp and to discharge the same through a pipe 36 at a point behind the back-fall, as at 35, in order to form a film of the thin 5 pulp and water between the surface of the tub 1 and the main body of the pulp as it rounds the ends of the midfeather, and thereby ease and speed the flow thereof. Moreover, by thus providing a more or less 10 strong suction or vacuum in the vicinity of the beater roll, I obtain the benefit of a materially increased circulation of the pulp, and at the same time a decreased expenditure of power.
- 15 As shown in Fig. 1, the tub 1 is preferably made circular in plan, and the midfeather is also substantially circular and hollow. At diametrically opposite points in the tub are located two beater rolls 3, each 20 supplied with a bed plate 5. By thus providing a circular channel for the stock, the latter circulates more rapidly and the beater rolls can be run faster, thereby turning out the product more expeditiously.
- 25 As shown in Figs. 4 and 5, the beater roll 3 is provided with a series of knives 17 spaced from each other sufficiently to make room for a row of lugs 38 between each pair of the knives, for the support of the fly 30 beaters 39 pivotally supported on a rod 40 loosely penetrating the beaters and lugs. Thus formed, the beater roll is enabled to give the pulp as it passes over the bed plate a more thorough flagellation and macera- 35 tion than is otherwise possible.
- As shown in Fig. 2, each beater roll 3 is provided with a vertically adjustable deflector 41 which is designed to rise and fall with the beater roll. To accomplish this, 40 the deflector is slidably carried by the hood 21 to move toward and from the back of the roll, and is connected with the lever arms 9 by suitable means, as rods 42 pivotally attached to the arm. Thus arranged, 45 the deflector remains at a uniform distance from the periphery of the roll whatever the adjustment in height given to the latter.
- A most important improvement in the bed- 50 plates is that shown in Fig. 6, which not only illustrates the knives 43 as extending through a wide arc beneath the roll 3, but as having their operative portions presented radially to the roll. This gives like cutting edges throughout the full extent of the bed-plate, 55 so that not only can all be shaped and ground exactly alike, but their coaction with the beater roll will be more uniform and perfect. Although I do not restrict myself thereto, I prefer to have the seat 44 on 60 which these knives rest concentric with the roll in order to have the knives all alike. Were the seat 44 horizontal, the knives would require to vary in dimensions and have the edges bent, as shown in Fig. 7, but 65 the operative portions of the knives are radi-

ally disposed. In Fig. 6, the knives 43 are illustrated as varying in thickness, those first met by the fly-bars being the thickest. The advantage of this is to have the knives 70 the strongest which bear the shock of the heaviest cutting. After the fibres have been first acted upon, the following knives can be thinner and hence nearer together and the number so much the larger in the same space.

As shown in Fig. 1, the approach of the stock to the beater rolls 3 is at an acute angle relative to the peripheries thereof, thereby aiding in the expulsion of the entrained air from the stock, and so rendering the 80 maceration thereof more perfect and expeditious.

As shown in Fig. 2, the hood 21 which is circular immediately above the crest of the back-fall, with its concave surface below, is 85 extended along the top edges of the side walls of the tub 1 tangential to the curvature, and thence on to a point beyond the foot of the back-fall. By thus providing the hood with a curvature concentric with 90 the crest of the back-fall, and an extension sloping downward and tangential thereto, the stock which is thrown up against this concave surface is made to pass forcibly along the surface of the extension instead of 95 permitting any portions of the stock to accumulate thereon. I have found that there is constant danger of the stock as it spatters against the hood as previously disposed, accumulating thereon and hardening, so that 100 after a time these dry lumps detach themselves, drop into the stock, and cause spots and "stips" in the resulting paper. The constant flow of stock along the under surface of the hood and its extension prevents 105 any such accumulations, while at the same time the extension shields any of the stock from spattering out over the top walls of the tub.

What I claim is:

1. A beating engine comprising a tub, a midfeather, a bed-plate, a beater roll having a supporting shaft, levers each pivotally supported at one end of each and having a rack at its other end, a shaft having pinions 115 meshing with said racks, and a weighted lever rigid with the last-named shaft, whereby the pressure of the said roll upon the bed-plate can be varied at will.

2. A beating engine comprising a tub, a beater roll, a bed-plate, a back-fall, and means for withdrawing the entrained air 120 from the ends of the bed-plate knives and discharging it upon the surface of the back-fall.

3. A beating engine comprising a tub, a beater roll, a bed-plate, a back-fall, the wall 125 of the tub being formed with an opening through it at an end of the knives of the bed-plate and the fly-bars of the roll, and 130

- means for withdrawing the entrained air from said knives and fly-bars during their mutual engagement and discharging it upon the rear surface of the back-fall.
5. A beating engine comprising a tub, a beater roll, a bed-plate, a back-fall, the wall of the tub having an opening through it at the end of the beater roll adjacent the bed-plate, and means for withdrawing the entrained air from the adjacent knives and fly-bars of said roll and bed-plate, and delivering it to the rear of the back-fall in a direction parallel with the surface of said rear.
10. A beating engine comprising a tub, a beater roll having fly-bars whose longitudinal lines are out of parallel with its axis, the tub having an opening through it at the end of the roll where its fly-bars last reach the bed-plate, a back-fall, a bed-plate, and means for withdrawing entrained air from the ends of the bed-plate knives and the fly-bars through said opening and discharging it to the rear of the back-fall.
15. A beating engine comprising a tub, a beater roll having fly-bars whose longitudinal lines are out of parallel with its axis, the tub having an opening through it at the end of the roll where its fly-bars last reach the bed-plate, a back-fall, a bed-plate, and means for withdrawing entrained air from the ends of the bed-plate knives and the fly-bars through said opening and discharging it to the rear of the back-fall.
20. A beating engine comprising a tub having an opening through one of its side walls, a beater roll having fly-bars out of parallel with its axis, the rearward ends of the fly-bars being adjacent said opening, a back-fall, a bed-plate, and means for withdrawing through said opening the air entrained between the fly-bars and bed-plate and delivering it to the rear of the back-fall parallel with the surface of the latter.
25. A beating engine having a beater roll, a bed-plate, a midfeather, a tub containing said midfeather and having a screened opening through its wall adjacent an end of the beater roll, and a fan pump connected with said opening.
30. A beating engine having a tub; a beater roll, a bed-plate, and means for creating a partial vacuum at an end of the beater roll.
35. A beating engine having a beater roll, a bed-plate, a tub provided with an opening adjacent an end of the beater roll, a screen for said opening, a fan pump connected with said opening for conveying the discharge from said opening back to the tub in the rear of the beater roll.
40. A beating engine comprising a tub, a beater roll, a bed-plate, a hood located over the beater roll and terminating in a catch basin, a screen composed of vertical bars suspended between the beater roll and the catch basin, and mechanical means for automatically wiping said bars.
45. A beating engine comprising a tub, a beater roll, a bed-plate, a hood located over the beater roll and terminating in a catch basin, a screen composed of vertical bars suspended between the beater roll and the catch basin, and mechanical means for automatically wiping said bars.
50. A beating engine comprising a tub, a beater roll, a bed-plate, a hood located over the beater roll and terminating in a catch basin, a screen composed of vertical bars suspended between the beater roll and the catch basin, and mechanical means for automatically wiping said bars.
55. A beating engine comprising a tub, a beater roll, a bed-plate, a hood located over the beater roll and terminating in a catch basin, a screen composed of vertical bars suspended between the beater roll and the catch basin, means for adjustably spacing said bars, and mechanical means for automatically wiping said bars.
60. A beating engine comprising a tub, a beater roll, a bed-plate, a hood located over the beater roll and terminating in a catch basin, a screen composed of vertical bars suspended between the beater roll and the catch basin, means for adjustably spacing said bars, and mechanical means for automatically wiping said bars.
65. A beating engine comprising a tub, a beater roll, a bed-plate, a hood located over the beater roll and terminating in a catch basin, a screen composed of vertical bars suspended between the beater roll and the catch basin, a rotatable shaft, and radial arms projecting from said shaft into wiping engagement with said bars.
70. A beating engine comprising a tub, a beater roll, a bed-plate, a hood located over the beater roll and terminating in a catch basin, a screen composed of vertical bars suspended between the beater roll and the catch basin, a tubular rotatable shaft, arms radially projecting from said shaft into wiping engagement with said bars, and means for supplying said shaft with water, the shaft being perforated to permit the water to reach said arms and bars.
75. A beating engine comprising a tub, a beater roll, a bed-plate, a hood located over the beater roll and terminating in a catch basin, a screen composed of vertical bars suspended between the beater roll and the catch basin, a tubular rotatable shaft, arms radially projecting from said shaft into wiping engagement with said bars, and means for supplying said shaft with water, the shaft being perforated to permit the water to reach said arms and bars.
80. A beating engine comprising a tub, a beater roll and a bed-plate, the tub having means for varying its angular position relative to the horizon.
85. A beating engine comprising a tub, a beater roll, and bed-plate, the tub having means for angularly varying the channel which delivers the stock of the beater roll for rendering the flow faster or slower.
90. A beating engine comprising a tub, a beater roll, a bed-plate, trunnions supporting the tub on an axis substantially that of said roll, and means for adjusting the tub upon said trunnions.
95. A beating engine comprising a tub, a beater roll, a bed plate, trunnions supporting the tub on an axis substantially that of said roll, and means embracing a screw rod and hand wheel for adjustably tilting said tub.
100. In a beating engine, a beater roll having longitudinally curved fly-bars adapted to present their convex edges to the bed-plate, the center of curvature of each fly-bar being between the planes of the ends of the roll.
105. In a beating engine, a beater roll having alternate rows of blades and pivotally supported beaters.
110. In a beating engine, a beater roll having spaced knives alternating with rows of lugs, and beater elements pivotally supported by said lugs.
115. In a beating engine, a bed-plate having a series of knives radially disposed relative to the beater roll and varying in thickness.
120. In a beating engine, a bed-plate having a series of knives varying in thickness, the lowermost knives being the thickest.
125. A beating engine comprising a tub, a beater roll, a back-fall having its topmost point above the level of the axis of the roll, a hood located above the back-fall, a movable deflector depending from the hood close to

the back surface of the roll, and means for moving the deflector in unison with the movements of the roll, said means embracing racks secured to the deflector, toothed 5 segments engaging the racks, and operative connection between the roll and segments.

24. A beating engine comprising a tub, a beater roll, pivoted levers supporting the roll, a back-fall having its crest above the 10 level of the axis of the roll, a hood located above the back-fall, a movable deflector depending from the hood close to the back surface of the roll, a pivotally supported lever, a connection between the latter and one 15 of the first-mentioned levers, and means whereby the movements of the second-men-

tioned lever correspondingly shift the deflector.

25. A beating engine comprising a tub, a beater roll, pivoted levers supporting the 20 roll, a back-fall, a hood located above the back-fall, a movable deflector depending from the hood close to the back surface of the roll, and levers pivotally supported and connected with the first-named levers and 25 the deflector, the connection with the deflector permitting of adjustment.

In testimony that I claim the foregoing invention, I have hereunto set my hand this 15th day of February, 1921.

LEO SHLICK.
